Attorney

JOHN GRAHAM, OF GRAFTON, WEST VIRGINIA.

Letters Patent No. 85,004, dated December 15, 1868.

IMPROVEMENT IN SIGNAL-LANTERNS.

The Schedule referred to in these Letters Patent and making part of the same.

To all whom it may concern:

Be it known that I, JOHN GRAHAM, of Grafton, in the county of Taylor, and State of West Virginia, have invented a new and improved Signal-Lantern; and I do hereby declare that the following is a full, clear, and exact description of the construction and operation of the same, reference being had to the accompanying drawings, making a part of this specification, in which—

Figure 1 is a vertical section, through the line *y y* of fig. 2.

Figure 2 is a horizontal section, through the line *z z* of fig. 1.

The object of this invention is to provide a simple, cheap, and convenient signal-lamp for railroad-use.

The use of the lamps heretofore employed upon railroads, for signalling at night, is attended with many inconveniences, which have rendered it desirable to find an instrument more completely adapted to such purposes.

First, their parts are easily dislocated by the jar of the engine, so that their accidental breaking is a matter of frequent occurrence.

Secondly, the light passing from them on every side, it is necessary to employ several lamps to give the several signals required, and, in general practice, two lamps are actually carried for each signal that has to be made.

Thirdly, their light is easily extinguished by gusts of wind, and with difficulty relighted; and

Fourthly, they being of common form and construction, and adapted to use elsewhere than on railroads, and for any ordinary purposes, they are frequently stolen.

These several evils are believed to be overcome by the lantern which I will now describe, and which has been in practical use, for several months, on one of the principal railroads of the country, and has been found to possess all the advantages anticipated from it.

In the drawings—

A represents the base of the lantern, and

B, a short vertical cylinder, firmly affixed to and supported by the base, and provided with a socket, to receive and hold the lamp C.

To the upper end of the part B, a square or polyhedral frame, D, is attached, having glass windows, W W, on some of its sides or faces, the outer sides *s s* being blank or opaque.

The windows may be of as many different colors as is required, and may be changeable, at pleasure, the panes of glass being held in position by cleats, *a a*, behind which they slide up and down, so that the work of inserting or removing them can be easily and almost instantaneously performed.

The opaque sides may be provided with sockets of a similar character, to receive and hold the spare panes of glass required to vary the signals, and such spare panes, when thus held in their sockets, may be pro-

tected by a sheet of tin or other covering over them, as shown at *e e*, a small slot or opening being made through the covering, in order that the glass may be readily pushed up, so as to be grasped by the hand when required for use.

Into such a lantern, the air necessary for combustion is supplied through horizontal pipes, I I, arranged along the floor of the lantern, or the top of the cylinder B, or through holes *m m*, made in the floor of the case D, outside of the rim of the part B.

The tubes are preferable for the purpose, inasmuch as they do not directly throw the air upon the flame of the lamp, and therefore protect the latter from being extinguished by a sudden gust of wind.

The chamber D is surmounted by a cylindrical dome, E, into which the heated air from the chamber rises through a tapering flue, F, and a deflector, G, is placed above the flue, and supported by standards *g g*.

The hot air escapes from the sides of the dome through apertures *n n*, while the cone F and deflector G prevent gusts of wind from extinguishing the flame from the upper end of the lantern.

A handle or bail, H, is attached to the dome.

The lamp is a small dipper-shaped vessel, having a handle, by which to insert or remove it, and having a flat-wick tube, J, provided with openings in the side, through which a pin may be inserted, to "pick up" or lower the wick, without removing the lamp from the lantern.

The whole instrument is made of tin, strengthened, if necessary, by wires, as in any tin-ware. It can thus be made at very little expense, while it is light, neat in appearance, and very strong and durable. Its parts are so put together, as above explained, that all danger of their dislocation or destruction, by the jar of the engine, is avoided.

The lantern is of such a form and character that it is not serviceable for any other purpose than that for which it is intended to be used, and hence is in less danger of being stolen than the old lanterns.

Its advantages over the old ones, in point of economy, convenience, &c., in enabling almost any number of signals to be made with a single lantern, will not need further explanation.

Having thus described my invention,

What I claim as new, and desire to secure by Letters Patent, is—

A signal-lantern, provided with sockets on the blank sides, covered or otherwise, to receive and hold the spare glasses, substantially as described.

To the above specification of my improvement, I have signed my hand, this 9th day of September, 1868:

JOHN GRAHAM.
